UNITED STATES PATENT OFFICE.

WILLIAM WEAVER, OF NORWALK, CONNECTICUT.

LOOM.

SPECIFICATION forming part of Letters Patent No. 576,174, dated February 2, 1897.

Application filed September 16, 1893. Serial No. 485,717. (No model.)

To all whom it may concern:

Be it known that I, WILLIAM WEAVER, a citizen of the United States, residing in Norwalk, Fairfield county, Connecticut, have invented certain new and useful Improvements in Looms, of which the following is a specification.

My invention relates to looms for weaving fabrics to be cut into strips to be used as weft in weaving a certain class of pile fabrics known as "chenille" fabrics; and it consists in means whereby threads of different characters or colors are automatically fed to the thread-gripper and carried across the warp.

It consists, further, in means whereby the weft-threads are automatically sheared at each edge of the fabric; and, finally, it consists in such novel features of construction hereinafter more fully set forth.

In the accompanying drawings, forming a part of this specification, and in which like letters and figures of reference indicate corresponding parts, Figure 1 is a front elevation of a loom embodying the invention as an entirety.

Fig. 2 is a side elevation of the invention. Fig. 3 is an elevation of the opposite side of the machine. Fig. 4 is a plan view of the invention, taken on the line 88 88 of Fig. 1. Fig. 5 is an enlarged vertical section of the mechanism for operating the thread-shifters. Fig.

5^a is a detail view, parts being broken away, showing the connection between the swords E², the lathe E, and the arrangement of the gears 5 and 5^a for driving the thread-carrier. Fig. 6 is a plan view thereof. Fig. 7 is a plan view of one end of the plate for supporting the thread-shifter, the thread-shifter being removed. Fig. 8 is an inverted plan view of the thread-shifter. Fig. 9 is a vertical sectional view thereof. Fig. 10 is a side elevation of the mechanism for operating the pattern-cylinders, the shears, and the thread-gripper. Fig. 11 is a detail perspective view of two of the slides for operating the thread-shifter mechanism. Fig. 12 is a detail view from the rear, showing the means for shifting the slide which carries the thread-shifter. Fig. 13 is a detail view of one of the levers and its cam for effecting said movement. Fig. 14 is a sectional elevation, taken on the line 13 13 of Fig. 10, of the pattern-cylinders and their operating mechanism.

Fig. 15 is a detail view, parts being broken away and in section, of the heddle-operating mechanism. Fig. 16 is a detail view of a section of one of the vertical heddle-operating levers. Fig. 17 is a horizontal sectional view of the operating-cylinder for the heddle mechanism, taken on the line 89 89 of Fig. 15. Fig. 18 is a side elevation of the said cylinder. Fig. 19 is a diagrammatic view of the method of manufacturing fabric, showing the preferred form of thread-shifter. Figs. 20, 21, and 22 are similar views of modified forms of thread-shifters. Fig. 23 is a plan view of the thread-gripper detached from the lathe of the loom. Fig. 24 is a horizontal sectional view thereof. Fig. 25 is a vertical sectional view of the same, taken on the line 90 90 of Fig. 23.

The method of operation of my invention is best indicated in the diagrammatic view, Fig. 19, in which X represents the warp-threads of the loom with a portion of the same interlocking with the weft-threads, forming a fabric.

J J' represent what I term "thread-shifters," each of the same being capable of supporting a number of threads. There are preferably, although not necessarily, two of said shifters, one on each side of the warp, and with said shifters I combine in a suitable manner means for moving the same, as described hereinafter. Between the shifters and across the warp travels a thread-carrier B, provided at one end with a thread-gripper 20 and at the opposite end with a similar gripper 21. Adjacent to each edge of the warp are shears or thread-cutters C. When the thread-carrier B is at one end of its travels, it grips one of the threads x presented by the thread-shifter, and as it travels to the opposite side it carries said thread between the warp until the gripper is at its opposite position, when the cutters will shear said thread at each edge of the fabric. The opposite gripper then grips the thread presented by the other thread-shifter, and as the carrier moves back the second thread is thrown between the warp and then again cut, and so on, the thread-shifters being moved from time to time so as to present a thread of the proper color or character at each operation.

It will be evident that the thread-shifters

may consist of a disk, as J or J', as shown in Fig. 19, which disk turns first in one direction and then in the other, or it may be a regular segment J^x, as shown in Fig. 20, or a reciprocating bar J^y, as in Fig. 21, or a series of separate radially-arranged arms J^z, as illustrated in Fig. 22. Each of these modified forms is provided with parts 30^a, adapted to be engaged and actuated by the series of 10 slides 17, hereinafter described, in the same manner in which the cross-plate 30 is actuated.

Having thus described the essential features of the operation, I will now describe the construction and arrangement of the devices which in practice have proved to be effective, reference being had to the remaining figures in the drawings.

A frame A is constructed in a suitable manner to support the thread-shifters J J', 20 the lathe E, the heddles F, the heddle-controlling cylinder F², and the devices for imparting the regular movements of these and other parts of the loom.

Upon the lathe E, which extends transversely across the forward part of the loom, moves the thread-carrier B, which is operated in substantially the same manner as that described in Letters Patent Nos. 342,408 and 342,409 granted to me. This thread-carrier, 30 as above stated, is provided at one end with thread-gripper 20 and at the opposite end with thread-gripper 21, the mechanism for automatically opening and closing which at the termination of each movement of the 35 thread-carrier B will be presently described.

D is the reed connected to the lathe E and projecting vertically therefrom.

E² F² represent the swords of the lathe, (see Figs. 2 and 5,) secured at their upper ends to 40 the under side of the lathe E and pivoted upon a transverse shaft 1 at their lower ends. On one end of the shaft 1 is a gear-wheel 2, which is engaged by a pinion 3, carried on the lower end of a vertical shaft 4. This shaft 45 is located at one side of the loom and is supported at its upper end by the lathe-sword E² and carries a gear 5 at its upper end, which meshes with a similar gear 5^a on the driving-shaft of the mechanism carried by the lathe 50 E for driving the thread-carrier, to which power is supplied from the driving-shaft through the gear 2, pinion 3, shaft 4, and gear 5. Journaled on the transverse shaft 1 is an eccentric-gear 6, meshing with a similar gear 55 7 on a parallel shaft 8, which in turn is operated from the shaft G² through a sprocket-chain 9. These eccentric-gears are so arranged as to throw the thread-carrier quickly through the warp-threads, but its driving 60 mechanism is driven at a reduced rate of speed while the thread-carrier is at the terminal points of its movement. A reciprocating motion is imparted to the lathe E through the pitmen 10, connected thereto and 65 to the cranks 110 on the shaft G'. The shafts G' and G² are arranged below a power-shaft G and in vertical alinement therewith, and

are driven therefrom by a series of gears G³, G⁴, and G⁵, secured, respectively, to the shafts G, G', and G².

H is a slide extending across the forward part of the loom and supported in a dovetailed groove in the frame. This slide carries on each end the thread-shifters J J', and is designed to be moved, preferably, at a variable speed alternately toward the edge threads of the warp. When the thread-carrier B reaches the terminal of its movement of the lathe E, it is beyond the edges of the warps and the lathe is rocked forward, bringing the thread-carrier into horizontal alinement with the thread-shifter. The gripper-jaws of the thread-carrier are then opened by mechanism hereinafter described and the thread-shifter is moved rapidly into close proximity to the thread-carrier by the movement of the slide H toward the edge of the warp. When the thread-shifter is brought adjacent to the thread-carrier, its movement is retarded, or it may be caused to cease moving altogether until after the weft has been gripped by the grippers 20 or 21 of the thread-carrier B and the thread-carrier starts on its movement across the warp, whereupon the slide continues its movement toward the edge of the warp, which it reaches about the same time as the thread-carrier does the opposite side, thus bringing the thread-shifters in close proximity to the shears C, when the weft-thread is cut and any loss of material prevented. The slide, and consequently the thread-shifters, is then in position to feed another thread to the thread-carrier B. The mechanism whereby the movement of this slide is effected, and shown clearly in Figs. 105 12 and 13, consists of two levers 11, pivoted one on each side of the loom, and to which a vertically-reciprocating movement is imparted alternately by cams 12, secured on the shaft G', to the ends of which levers cords 13 are 110 connected, which pass over friction-pulleys 14 on the loom-frame and in turn are connected to a lug 15, secured to the center of the slide H.

As before indicated, it is necessary to shift 115 the thread-shifters or each thread-shifter when it is desired to grip a thread of different color or character from that previously woven, and I therefore combine with each thread-shifter suitable means for first bringing it to 120 proper position and then holding it in its shifted position as long as it may be necessary for the thread-carrier to grip rapidly any one particular thread. Various means for automatically shifting the position of the thread-shifters will suggest themselves to skilled mechanics. The means shown consists of a primary pattern-card or belt K, passing over a primary pattern-cylinder K', in connection with a reciprocating cross-head L, Fig. 5, 130 which in its forward movement makes contact with a shoulder or lug 16 upon any one of a series of slides 17, so that when by the action of the pattern belt or card any slide is

thrown up it will be in position for its shoulder to be engaged by the cross-head during its forward movement. The next or return movement of the cross-head L will strike the lug 18 on the slide and push it back to its normal position. Each slide 17 is provided with a vertical arm 19, and all of these arms are in position to make contact with a cross-plate 30, which is connected with the devices for rotating the thread-shifters J J', and which I will now describe. The cross-plate 30 is connected to and depends from the end of a rack 31, (see Figs. 6 and 7,) engaging a pinion 32, which in turn engages with a cog-wheel 33 upon a shaft 34, upon which the thread-shifter is journaled.

35 is a segmental groove in the lower face of the thread-shifter, (see Figs. 8 and 9,) which is engaged by a pin 35^a on the cog-wheel 33, forming a connection between the thread-shifter and cog-wheel 33 and insuring the rotation of the former when the cog-wheel is rotated, the groove 35 permitting the cog-wheel and its operating devices to be returned to their normal position independent of the thread-shifter by means of a spring 31^a, connected at its opposite ends to the cross-plate 30 and to the guide 31^c, respectively. The rack 31 extends through this guide 31^c, which surrounds it on three sides (see Figs. 6 and 7) and engages an idle pinion 32^a, which serves to prevent binding or displacement of the rack-bar during its reciprocating movement.

In order to hold the thread-shifter in any position to which it is rotated, a spring-pressed pawl 36, pivoted on the slide H, adjacent to and designed to engage ratchet-teeth 36^c on the under side of the thread-shifter, is provided, this pawl being released from contact with the teeth upon the return of the thread-shifter from the edge of the selyage by means of a centrally-pivoted tailpiece 37, a pin on one end of which normally engages the pawl 36, and its other end projecting beyond the edge 45 of the slide H to engage a lug 38 of the frame as the slide H is reciprocated. The pawl 36 and the tailpiece are kept normally in engagement by means of a spring 37^a, the ends of which bear upon the said pawl and the outer 50 end of the tailpiece, respectively. This arrangement of the tailpiece with respect to the pawl is such that when the end of the slide upon which they are secured is moved toward the lug 38 in engagement therewith the end 55 of the tailpiece will be moved into a recess 36^a in the pawl, permitting the tailpiece to spring past the lug 38 without affecting the pawl. Upon the return movement of the slide, however, the tailpiece will engage the lug upon 60 its opposite side, which will move the inner end of said tailpiece, or that which engages the pawl in the opposite direction, thus throwing the pawl out of engagement with the ratchet-teeth of the thread-shifters. The 65 thread-shifter when so released is returned to its normal position by a helical spring 39, se-

cured to the shaft 34 and to a cross-piece 40 of the thread-shifter.

Secured to the under face of each thread-shifter J J' on each side of the thread-openings therein are vertical strips or guides 38^a, projecting downward from the thread-shifters in pairs parallel with each other. These strips are separated by a space sufficiently wide to permit the opened gripper-jaws 20 21 75 to be thrust between them to seize the thread and serve to keep the threads from being pushed to one side of the grippers.

The manner in which each slide 17 is lifted from the primary pattern-belt to engage the 80 depending cross-plate 30, and the lugs 16 and 18 lifted to be engaged by the reciprocating cross-head, is as follows, reference being had particularly to Figs. 5 and 11 of the drawings, the former of which figures shows one of the 85 slides thrown in its elevated position by its jack and pushed into engagement with the cross-plate 30 by the reciprocating cross-head L, while the other slide rests in its normal position.

The slides 17, which correspond in number to the different colors or characters of threads to be used, are arranged in a guiding-frame and adjacent to each other, each slide being provided, as above described, with lugs 16 and 18 and a vertical arm 19, all of which are arranged on their upper faces. Engaging grooves in the lower faces of said slides (shown in dotted lines, Fig. 11) are a series of pivoted jacks 22, one of which is provided for 90 each slide and each of which has one of its ends projecting over the pattern-cylinder K'. Passing through the end of each of these jacks is a vertically-movable jack-needle 23, the lower end of which rests on the primary 100 pattern-belt K. Each of the needles 23 is encircled by a spring 23^a, which bears at its lower end upon the upper face of the jack 22 by means of a collar on said needle and at its upper end against a frame A, the purpose of 105 said springs 23^a being to thrust the points of their needles through the perforation of the pattern-belt K when they are moved into alignment with the points of the needles and to simultaneously lower the forward end of 110 that one of the jacks 22 whose needle is lowered. The primary pattern-cylinder K' is thickly perforated, (see Fig. 14,) while the primary pattern-belt K is perforated in accordance with the pattern which it is desired 115 to weave. From this it will be seen that when one of the perforations is brought into alignment with one of the needles 23 the latter will drop through the perforation in the primary pattern belt and cylinder and cause its jack 120 22 to swing and elevate one of the slides 17 into the path of movement of the reciprocating cross-head L, which engages the lug 16 thereon and moves the slide forward, and consequently rotates the thread-shifter. The 125 130 cross-head L moves in slots in the sides of the slide-guiding frame and extends horizontally

across all of the slides, movement being imparted to it from a cam 24 on the shaft G² through a series of levers 25^a 25^c and connecting-links 25 and 25^b. The lever 25^c is pivoted on the shaft G' and is operated by the cam 24 to throw the cross-head L, to which the link 25 is connected, forward at the proper time, the said lever 25^c and link 25 being connected by the intervening link 25^b and lever 25^a.

As it is necessary that the length of the rotary movement of the thread-shifter, which movement is effected indirectly through the slides 17, shall differ according to the color or character of the thread to be presented to the thread-carrier B, the lengths of the movements of the slides 17 will of necessity have to differ. This is effected by graduating the spaces between the lugs 16 and 18 on each slide so that the space between the lugs on the second slide will be a little longer than that on the first and the space between the lugs on the third slide longer than that on the second, and so on, as shown in Fig. 11. Thus it will be seen that if the first slide is capable of being moved three inches the next one will be allowed to move only two and one-half inches, the next two inches, and so on, the movement of each slide being less than the preceding one, for the reason that the lugs 16 on the slides 17 are so situated that the one on the first slide is engaged by the cross-head L sooner than that on the second, and that on the second slide sooner than that on the third. The length of movement of the cross-head L is always the same, but the movements of the slides 17 are varied by the cross-head engaging the first slide sooner than the second, and consequently it has to carry it a greater distance than it would the second slide, by reason of its not engaging said second slide before having completed more of its movement.

It frequently happens that the thread-shifter must be successively shifted to the same position, such being the case when it is desired to successively lay weft-threads of the same character or color without changing. In order that this may be effected without the necessity of using a large pattern-belt or other pattern devices, I make use of what I call a "director" or "supplementary pattern-belt," which has the office of bringing the thread-shifter to the same position during the action of the director or supplementary pattern-belt. The said director is a belt 50^a, and the devices for operating the director consist of a pattern-cylinder 50, over which the pattern-belt 50^a passes. This cylinder is journaled on a shaft 51, parallel to and arranged in the rear of that which carries the primary pattern-belt K, and is provided with an annular series of perforations formed centrally around its periphery. Arranged vertically above the pattern-cylinder 50 and in alinement with the perforations therein is a needle-bar 52. (See Figs. 5 and 10.) This bar 52 carries in

its upper end a friction-roll which is engaged on its under side by a cam-shoe 70 of the swinging frame N for raising and lowering it alternately.

53 is a horizontally and longitudinally reciprocating slide through a slot 54, in which the said needle-bar 52 passes, said needle-bar being connected to the said slide by means of a link 55, pivoted to both the slide and needle-bar. Through this link a reciprocating movement is imparted to the slide by the vertical movement of the needle-bar.

The swinging frame N, referred to above, is pivoted at its lower end to the base of the loom and receives an oscillatory movement from a cam 71 on the shaft G² through link 72 and lever 72^a, the latter of which is in engagement with the cam 71 and is pivoted at its lower end to the frame A and at its upper end to the link 72. This swinging frame carries on its forward end a pawl 73, designed to engage a ratchet-wheel 74 on the shaft of the primary pattern-cylinder K'. This pawl 73 when out of action or during the period when the needle-bar 52 is in an elevated position rests upon the end of the slide 53. When the needle-bar is lowered by reason of a perforation in the director or pattern belt being rotated beneath its needle, the slide 53 is withdrawn from beneath the pawl 73, and it drops into engagement with the ratchet-wheel 74 and at the next forward movement of the swinging frame N it turns it one step, and consequently rotates the primary pattern-cylinder K' and belt K a corresponding distance. The needle-bar is then lifted from the director pattern-belt by the action of the cam-shoe 70 thereon at the next or rear movement of the swinging frame, and the director pattern-cylinder 50 and pattern-belt 50^a are moved forward one step by means of a pawl 56, carried on the swinging frame N and designed to engage a ratchet-wheel 57 on the director-shaft 51. This pawl during the forward movement of the swinging frame is withdrawn from engagement with its ratchet-wheel upon a horizontal plate 58 and, as above stated, engages the ratchet-wheel 57 only at every rearward movement of the swinging frame N. From this it will be seen that only when the needle-bar 52 descends through a perforation in the director pattern-belt is the primary pattern-belt K rotated and the color or character of the thread being fed to the thread-carrier B changed, while the director-cylinder 50 and its pattern-belt is rotated at every rearward movement of the swinging frame N. In other words, as long as the needle-bar 52 is in an elevated position the rotating mechanism of the primary pattern-cylinder K' is non-active, and consequently the same jack-needle 23, which has been previously lowered, is caused to engage the same opening in the primary pattern-belt K' and to repeat such engagement until the needle-bar 52 is lowered and the rotating mechanism of the pattern-cylinder allowed to operate

said cylinder. Thus it will be seen that when the needle-bar is elevated the thread-shifters are caused to repeat the feeding of one thread during the continuance of such elevation of 5 the needle-bar 52.

As it is necessary that the needles 23 shall be elevated from engagement with the primary pattern-belt K at each movement of the swinging frame N, a pivoted lifting-plate 26 10 is provided, which is lifted at each forward movement of said swinging frame by means of an arm 27 and connecting-rod 28, pivoted to said arm at one end and to the swinging frame N at the other.

15 The jacks 22, through which the needles 23 pass, rest on the lifting-plate whenever the needles drop into a perforation of the pattern-roll, and consequently whenever the lifting-plate 26 is elevated, as described above, the 20 jack which rests upon it will be elevated and returned to its normal position.

As hereinbefore stated, the thread-carrier B is provided with grippers 20 21 at the ends thereof, one of these grippers being designed 25 to open and thereby release the thread which it has just drawn across the warp, while the other one seizes the thread which has been fed into it by the thread-shifter preparatory to drawing it across the warp. Any suitable 30 means may be employed for opening and closing the grippers 20 21 at each side of the warp, but I will now describe those which I have found to be the most effective. The mechanism whereby this is effected, reference 35 being had particularly to Figs. 23, 24, and 25 of the drawings, consists of the thread-carrier B, in the shell of which the grippers 20 21 are pivoted, each of which grippers is composed of two jaws S and S'. Springs 82, arranged 40 in recesses in the shell of the thread-carrier B on either side of the gripper-jaws S S', serve to keep these arms in their normally-closed position. Formed in the jaws S S' of the grippers at a point about midway of their 45 ends, and in their opposing faces, are notches forming together circular openings 83, which taper toward their lower ends. Arranged above these openings and supported on the lower faces of overhanging plates 85, in vertical alignment therewith, are pins 84. These pins when forced into the openings 83 force the jaws of the grippers apart laterally in opposition to the springs 82. Secured to each 50 of the overhanging plates 85 are arms 86, and the ends of these arms are pivoted near the ends of the thread-carrier casing, these arms passing beneath a plate 87, arranged centrally in said thread-carrier casing, and which is designed to be depressed. From this it 55 will be seen that when the plate 87 is depressed the pins 84 will be forced between the gripper-jaws and force them apart, and when this pressure is removed the springs 82 will return the jaws to their normal closed position.

88, Figs. 1, 2, 3, 5, 6, and 10, is an arm pivoted at its center to the frame A of the loom,

one end of which carries a friction-roll 89, designed to engage the central depressing-plate 87 of the thread-carrier B when the lathe of 70 the loom is thrown in its forward position and the thread-carrier is at either end of its movement. The other end of this arm 88 is pivoted to a slide 89^a, depending loosely therefrom at approximately right angles. In this 75 slide is an L-shaped slot 90, (see Fig. 10,) in the short portion of which rests a pin extending from lever 91. This lever 91 is pivoted at one end to the frame A of the loom and has an enlargement 92 on its under side, 80 which is engaged by a friction-roll 93 (see Figs. 2 and 3) on the sword E² of the lathe E to lift the slide 89^a and depress that portion of the arm 88 which carries the friction-roll 89.

94 is a spring attached to the slide 89^a for 85 holding the pin from the lever 91 in engagement with the short portion of the L-shaped slot 90. From this it will be seen that every time the lathe E is thrown forward or toward the breast-beam the friction-roll 93 will engage the enlargement 92 of the lever 91 and raise said lever, which will in turn lift the slide 89^a by virtue of the engagement of its end with short portion of the L-shaped slot 90. This upward movement of the slide will 95 cause the outer end of the arm 88 to be lowered and the friction-roll 89 to bear upon the depressing-plate 87 and simultaneously open the grippers 20 21 of the thread-carrier.

In order to release the slide 89^a to permit 100 it to drop to its normally-lowered position, it is provided on its inner edge with a beveled lug 89^b, horizontally alined with a similar lug 30^a on the cross-plate 30, (see Figs. 1, 2, 5, 6, and 10,) which comes in contact with the lug 105 89^b when the thread-shifter is moved toward the edge of the warp. When these two lugs contact, the lug 89^b and its slide 89^a is thrown outward, which movement causes the pin of the lever 91 to be moved out of engagement 110 with the short portion of the slot 90 into the long or vertical portion thereof, whereupon the slide 89^a will drop by gravity to its lowered position subsequently to the return of the lathe E from its forward to its rear position. 115 When the lathe is moved back to its rear position, however, the end of the arm 91, which carries the pin, will be lowered, causing the pin to register with the short portion of the L-slot, whereupon the slide is drawn 120 inward by its spring 94, and thus the reengagement with the pin of the lever 91 is effected preparatory to again lifting the slide 89^a.

The thread-cutters C C, arranged adjacent 125 to the edge threads of the warp, are constructed and operated as follows, reference being made particularly to Fig. 10 of the drawings:

The thread-cutters are each composed of two cutting-blades 95, pivoted together. One 130 of these blades is fixed stationary to the frame of the loom, while the other is attached by means of a lever 96 to an arm 97 on one end of a shaft 98. This shaft carries on its op-

posite end a similar arm 99, which in turn is connected by a link 100 to the lever 91, just described. It will be seen from this description that at every upward movement of the lever 91, in consequence of the action of the friction-roll 93 thereon, the blades of the cutters C C will be forced together, severing the thread which has just been drawn across the warp from the opposite side by the thread-carrier and thrown between them by the forward movement of the lathe E.

Any of the usual heddle-operating mechanisms may be employed in connection with my improved loom. I prefer, however, to construct the heddle-operating devices in the manner in which I will now describe and which is illustrated fully by Figs. 15, 16, 17, and 18 of the drawings.

Broadly speaking, the heddle mechanism used consists of an operating-cylinder around the periphery of which is arranged a series of friction-rolls. These friction-rolls are rotated into contact with a series of vertically-disposed longitudinally-movable levers corresponding in number to the series of friction-rolls on the operating-cylinder, and each of which is connected to one of the heddles. These rolls push the levers inward and bring a spring-actuated clip of each lever operated into the path of movement of a vertically-reciprocating cross-head, which engages said clip and throws the lever downward and raises the heddles. The return or upward movement of the cross-head has the office of returning the heddles to their normal position.

F² represents the operating-cylinder having an annular series of friction-rolls g arranged around its periphery, said annular series being also arranged parallel to each other, one annular series for each heddle. A step-by-step rotary movement is imparted to this cylinder from a cam g' on the driving-shaft G² by means of a short lever k², pivoted to the frame A and connected to be reciprocated vertically by said cam. To the free end of this lever a bar g² is connected, which extends vertically upward and is in turn connected to an angle-bar k³, centrally pivoted upon the shaft of the cylinder F² and carrying a pawl g³ thereon, which engages a ratchet-wheel k⁴ upon the said shaft. Thus whenever the lever k³ is lowered by the cam g' the bar g² is correspondingly moved thereby, causing the pivoted angle-bar k³ and its pawl g³ to be rocked and the ratchet-wheel k⁴ and the cylinder F² to be rotated one step. Arranged vertically and adjacent to the operating-cylinder, one for each series of friction-rolls g, are levers g⁴, passing through guides at their lower ends and connected to horizontal pivoted levers g⁵ at their upper ends. These horizontal levers are each connected to the top of one of the heddle-frames g⁶, the lower sides of these frames being attached alternately to the opposite ends of cords g⁷, (see Figs. 1, 2, and 3,) passing around pulleys

g⁸, secured to opposite ends of cords g¹⁰, which pass around rollers g¹² on the under side of and extending transversely across the base of the loom. One end of each of the cords g⁷ (there being one on each side of the loom for each two heddle-frames used) is secured to the lower side of one of the heddle-frames, while its other end is secured to the lower side of the next succeeding heddle-frame, as is usual, in order that when one of the heddle-frames is elevated by the action of its operating mechanism the next succeeding one will be depressed. Reciprocating vertically in a slot h in one of the loom side frames is a cross-head h², connected to a rod h³, which is operated at its lower end by a cam h⁴ on the shaft G². The upper end of the rod h³ is broadened at h⁵ (see Fig. 3) and bears upon the under side of the horizontal levers g⁵, the purpose of which will presently appear. Pivoted in a recess in each lever g⁴ and projecting from the inner face thereof are spring-pressed clips i.

From the above-described mechanism it will appear that when one of the friction-rolls g of the operating-cylinder is rotated into contact with its lever g⁴ it will push it inward and throw the clip i thereon into the path of movement of the cross-head h², which will tend to carry the lever downward and through the horizontal levers g⁵ lift one of the heddle-frames, or as many of them as there are levers engaged by the cross-head. When the cross-head starts on its return or upward movement, the plate h⁵ of the rod h³, engaging the horizontal levers g⁵, will return them to their normal position. In order to insure the return of these levers g⁵ and to equalize the strain they impose upon their operating-rods g⁴, a link j is pivoted to the rod h³ and to lever j². This lever j² is pivoted centrally to the frame of the loom and its free end engages one end of a pivoted lever j³, the other end of which bears against the under side of the lever g⁵. Thus arranged, whenever the plate h⁵ is lowered by the downward movement of the cross-head h² the lever j³ is caused to be correspondingly elevated and to be lowered when said plate is elevated. This action holds the lever j³ always in contact with the forward ends of the levers g⁵ and prevents them from dropping below their normal position and also relieves the strain in some measure from the lever g⁴.

I have shown what I believe to be the best means, all things considered, of weaving chenille filling strips or fabrics by wholly automatic means, thus avoiding the employment of a large number of drop-boxes, which would be necessary, if a great number of colors are used, or of shifting the colors by hand.

The advantages of the several parts of my invention will be appreciated by those skilled in the art to which it appertains, and within the scope of my invention, as defined in the following claims, modifications may be made

in the form, construction, and position of the parts and some features of my invention used without the others, since

What I claim is—

- 5 1. In a loom, the combination of one or more thread-shifters, mechanism for shifting the same to cause a proper thread to be presented to the thread-carrier, means for moving the thread shifter or shifters bodily toward the edge of the warp, a thread-carrier and means for reciprocating the thread-carrier across the warp, substantially as described.
- 10 2. In a loom, the combination of the thread-shifters arranged one on each side of the warp, mechanism for shifting the same to cause a proper thread to be presented to the thread-carrier means for moving said thread-shifters bodily alternately toward the edge of the warp, and a thread-carrier and means for reciprocating the thread-carrier across the warp, substantially as described.
- 15 3. The combination in a loom of one or more thread-shifters arranged one on each side of the warp, mechanism for shifting the same to present a proper thread to the thread-carrier, means for moving said thread shifter or shifters bodily at a variable speed toward the edge of the warp, a thread-carrier, and means to reciprocate the thread-carrier across the warp, substantially as described.
- 20 4. In a loom, the combination of the thread-shifters arranged one on each side of the warp, mechanism for shifting the same to cause a proper thread to be presented to the thread-carrier, devices for supporting the thread-shifters, means for reciprocating said supporting devices, whereby the thread-shifters are brought bodily to the edge of the warp alternately, a thread-carrier, and means for reciprocating it across the warp, substantially as described.
- 25 5. The combination in a loom, of a slide, the thread-shifters supported thereon, one on each end thereof, means for moving said slide to bring the thread-shifters bodily to the edges of the warp alternately, and a thread-carrier and means for reciprocating the thread-carrier across the warp, substantially as described.
- 30 6. The combination in a loom, of a slide, the thread-shifters supported one on each end thereof, the cams and their shaft, mechanism connecting said cams and slide, whereby the latter is caused to reciprocate to bring the thread-shifters bodily to the edges of the warp alternately, and a thread-carrier and means for reciprocating the thread-carrier across the warp, substantially as described.
- 35 7. A loom provided with one or more thread-shifters arranged one on each side of the warp, a thread-carrier and means for reciprocating the same across the warp, a perforated primary pattern-belt, a perforated cylinder upon which said belt is supported, intermediate mechanism between the thread-shifters and the primary pattern-belt for

shifting the thread-shifters to cause a proper thread to be presented to the thread-carrier, a secondary or director pattern-belt, a cylinder upon which said belt is supported, devices between said secondary and primary pattern-belts whereby the movement of the latter is controlled by the former, substantially as described.

8. A loom, provided with one or more thread-shifters arranged one on each side of the warp, primary pattern devices means for imparting movement to the primary pattern devices, mechanism intermediate of the thread-shifters and the primary pattern devices, pattern-controlled devices adjacent to the primary pattern devices for throwing the same out of movement to cause a thread of one color or character to be repeatedly fed to the thread-carrier and for throwing them into movement to cause a thread of a different color or character to be fed to the thread-carrier, a thread-carrier and means for reciprocating the same across the warp, substantially as described.

9. In a loom, the combination of the cutters arranged upon each side thereof adjacent to the edge threads of the warps, thread-shifters arranged one on each side of the warp, a thread-carrier, means for reciprocating it across the warps, and devices for moving the thread-shifters alternately to the edges of the warps, simultaneously with the movement of the thread-carrier toward the opposite side thereof and for maintaining them in said position until the thread-carrier starts on its return movement, substantially as described.

10. In a loom, the combination of one or more thread-shifters, a series of independently-movable slides, devices between the slides and thread-shifters adapted to be acted upon by any one of said series of slides, mechanism for moving said slides to cause the thread-shifters to be shifted, pattern devices, and devices intermediate of the pattern devices and slides whereby the latter are thrown into engagement with their moving mechanism, substantially as described.

11. A loom provided with one or more thread-shifters arranged one on each side of the warp and each supporting a series of threads of different colors or characters, a thread-carrier and means for reciprocating it across the warp, a primary pattern-belt provided with parallel series of perforations, a series of needles for engaging the perforations of the primary pattern-belt, devices between the needles and thread-shifters, a secondary or director pattern-belt, a needle-bar for engaging said belt, means for moving said needle-bar into and withdrawing it from engagement with the director pattern-belt and devices intermediate of the needle-bar and primary pattern-belt whereby the movement of the latter is controlled by that of the former, substantially as described.

12. A loom provided with one or more thread-shifters arranged one on each side of

the warp and each supporting a series of threads of different colors or characters, pattern devices, mechanism intermediate of the thread-shifters and the pattern devices adapted to be operated by the said pattern devices and to be operated independently thereof, means for operating said mechanism independently of the pattern devices to shift the thread-shifters, a thread-carrier and means for reciprocating it across the warp, substantially as described.

13. In a loom, the combination of one or more thread-shifters arranged one on each side of the warps, mechanism for shifting the thread-shifters to present a proper thread to the thread-carrier, a primary pattern-belt, a series of needles for engaging said belt, devices for elevating said needles out of engagement with said pattern-belt, mechanism intermediate of said needles and thread-shifter for shifting the latter, secondary or director pattern devices for regulating the movement of the primary pattern-belt, devices between the primary pattern devices and secondary pattern devices, and a thread-carrier and means for reciprocating it across the warp, substantially as described.

14. In a loom, provided with one or more thread-shifters, a series of slides, mechanism between the slides and thread-shifters for shifting the latter to cause a proper thread to be presented to the thread-carrier, a primary pattern-belt, devices between the slides and pattern-belt for operating said slides, and director pattern devices for regulating the movement of said primary pattern-belt, a thread-carrier and means for reciprocating it across the warp, substantially as described.

15. A loom, provided with one or more thread-shifters arranged one on each side of the warp and each supporting a series of threads of different colors or characters, primary pattern devices, mechanism intermediate of the thread-shifters and primary pattern devices, said mechanism adapted to be operated by said pattern devices and to be operated independently thereof, means for operating said intermediate mechanism independently of the primary pattern devices to shift the thread-shifters, director or secondary pattern devices, devices between the secondary and primary pattern devices whereby the movement of the latter is controlled by that of the former, a thread-carrier and means for reciprocating it across the warp, substantially as described.

16. In a loom, the combination of the thread-shifters arranged one on each side of the warps, means for shifting the same to cause a proper thread to be presented to the thread-carrier, mechanism for moving the thread-shifters bodily to the edge of the warps, cutters arranged on each side of the warp, a thread-carrier and means for reciprocating it across the warp.

17. In a loom, the combination of the thread-shifters arranged one on each side of the warp,

means for shifting the same to cause a proper thread to be presented to the thread-carrier, mechanism for moving the thread-shifters when in their shifted position bodily to the edge of the warp, means for returning the thread-shifters from their shifted to their initial positions, cutters on each side of the warp, a thread-carrier and means for reciprocating it across the warp, substantially as described.

18. In a loom, the combination of the thread-shifters arranged one on each side of the warp, mechanism for shifting the same to cause a proper thread to be presented to the thread-carrier, means for moving said thread-shifters alternately bodily toward the edge of the warp, cutters arranged one on each side of the warp, means for alternately operating said cutters, a thread-carrier and means for reciprocating it across the warp, substantially as described.

19. In a loom, the combination of the thread-shifters arranged one on each side of the warp, mechanism for shifting the same to cause a proper thread to be presented to the thread-carrier, means for moving the thread-shifters toward the edge of the warp, cutters arranged on each side of the warp, a lathe and mechanism for reciprocating it toward the cutters, a thread-carrier carried upon the lathe, and means for reciprocating it across the warp, substantially as described.

20. A loom provided with one or more thread-shifters arranged one on each side of the warp, guides on the thread-shifters extending upon each side of the thread for preventing the deflection thereof, a thread-carrier having grippers adapted to be thrust between said guides to grip the thread, and means for reciprocating the thread-carrier across the warp, substantially as described.

21. In a loom, the combination of the thread-carrier, the gripper-jaws thereon which normally rest together, a depressing-plate also carried upon the thread-carrier and connections between the depressing-plate and gripper-jaws whereby said jaws are forced apart when the depressing-plate is depressed, and means for depressing said plate as the thread-carrier reaches a terminal of its movement, substantially as described.

22. In a loom, provided with one or more thread-shifters arranged one on each side of the warp, mechanism for shifting the same to cause a proper thread to be presented to the thread-carrier, guides on the thread-shifters extending upon each side of the thread for preventing the deflection of the thread to insure its being gripped by the grippers of the thread-carrier, a thread-carrier having grippers adapted to be thrust between said guides to grip the thread, means for opening and closing the grippers and means for reciprocating the thread-carrier across the warp, substantially as described.

23. A loom, provided with one or more thread-shifters, a cross-plate and devices between the cross-plate and thread-shifters, a

- series of independently-movable slides, each provided with a vertical arm for engaging said cross-plate, and with a lug, a reciprocating cross-head for engaging said lugs, 5 means for reciprocating said cross-head, and pattern - controlled mechanism for lifting said slides into position to be engaged by the said cross-head, substantially as described.
24. In a loom, the combination of the thread-shifters, arranged one on each side of the warp, a cross-plate, devices for connecting the cross-plate with the thread-shifters, pattern devices, a series of independently-movable slides adapted to engage the cross-plate, 10 a reciprocating cross - head and means for moving the same, and a series of jacks and needles engaging the slides and pattern-belt of the pattern devices respectively, substantially as described.
25. In a loom, the combination of one or more thread-shifters, arranged one on each side of the warp, a series of slides capable of independent vertical and horizontal movement, and mechanism between the slides and thread-shifters for moving the latter by the horizontal movement of the former, a pattern-belt, devices between the slides and pattern-belt for elevating the slides, and mechanism for imparting a horizontal movement thereto, substantially as described.
26. A loom, provided with one or more thread-shifters, arranged one on each side of the warp, pattern devices, mechanism between the pattern devices and thread-shifter for shifting the latter, and devices independent of the shifting mechanism of the thread-shifters for returning said thread - shifters from their shifted to their normal position, substantially as described.
27. In a loom, provided with one or more thread-shifters, a series of independently-movable slides arranged below the same, devices between the slides and thread-shifter for shifting the latter, pattern devices, a cross-head and means for reciprocating the same, and mechanism between the pattern devices and slides for lifting said slides into the path of movement of the cross-head, substantially as described.
28. In a loom, the combination of one or more thread-shifters arranged one on each side of the warp, a series of independently-movable slides, a cross-plate adapted to be acted upon by any one of said series of slides, devices between the cross-plate and thread-shifters, a reciprocating cross-head adapted to move said slides, means for reciprocating said cross-head and pattern devices for throwing the slides into engagement with the reciprocating cross-head, substantially as described.
29. In a loom, the combination of the thread-shifters, arranged one on each side of the warp, the cross-plate, and devices between the cross-plate and thread-shifters, a series of slides capable of vertical and horizontal movement, mechanism for moving said slides ver-

tically, a reciprocating cross-head for moving said slides horizontally, and means for reciprocating said cross-head, substantially as described.

30. A loom provided with a thread-shifter, a series of slides, each slide being capable of vertical and horizontal movement independent of the others, only one of the slides being movable at the same time, devices intermediate the thread-shifter and said slides adapted to be engaged by the latter to actuate the thread - shifter, and mechanism for moving said slides vertically and horizontally, substantially as described.

31. In a loom, the combination of one or more thread-shifters arranged one on each side of the warp, mechanism for shifting the thread-shifters to cause a proper thread to be presented to the thread-carrier, means for locking the thread-shifters in their shifted positions for a predetermined time, and for releasing them at the end of such period, a thread-carrier and means for reciprocating it across the warp, substantially as described.

32. In a loom, the combination of the thread-shifters, arranged one on each side of the warp, mechanism for shifting the same to cause a proper thread to be presented to the thread-carrier, means for locking the thread-shifters in their shifted position for a predetermined time and for releasing them at the end of such period, cutters arranged on each side of the warp, a thread-carrier and means for reciprocating it across the warp, substantially as described.

33. In a loom, the combination of the thread-shifters arranged one on each side of the warp, mechanism for shifting the same to cause a proper thread to be presented to the thread-carrier, means for locking the thread-shifters in their shifted position for a predetermined time and means for releasing them at the end of such period, devices for moving the thread-shifters to the edge of the warp, cutters arranged on each side of the warp, a thread-carrier and means for reciprocating it across the warp, substantially as described.

34. In a loom, the combination of one or more thread-shifters, a perforated primary pattern-belt, a plurality of needles, means for throwing said needles into engagement with the perforations of said belt, devices for elevating said needles above the primary pattern-belt at regular intervals, mechanism between the needles and the thread-shifters, director pattern devices adapted to control the movement of the primary pattern-belt whereby the shifting mechanism of the thread-shifter is caused to continue shifting the thread-shifters to one position in order that a thread of one color or character may be repeatedly fed to the thread-carrier, and to throw the primary pattern-belt into movement when it is desired to change the color or character of the thread, a thread-carrier and means for reciprocating it across the warp, substantially as described.

35. In a loom, the combination of one or more rotary reciprocating thread-shifters arranged one on each side of the warp, mechanism for shifting said thread shifter or shifters to cause a proper thread to be presented to the thread-carrier, the springs for returning said thread-shifters from their shifted to their normal positions, a thread-carrier and means for reciprocating it across the warp, 10 substantially as described.

36. In a loom, the combination of one or more thread-shifters arranged one on each side of the warp, mechanism for shifting the thread shifter or shifters to cause a proper thread to be presented to the thread-carrier, means for locking the thread-shifters for a predetermined time when the desired thread has been brought in position to be gripped by the thread-carrier and for retaining the 15 thread-shifters in their shifted position until the thread-carrier has traveled to the opposite side of the warp, a thread-carrier and means for reciprocating it across the warp, substantially as described.

37. In a loom, the combination of one or more thread-shifters arranged one on each side of the warp, mechanism for shifting the thread-shifters to cause a proper thread to be presented to the thread-carrier, means for locking the thread-shifters when the desired thread has been brought in position to be gripped by the thread-carrier and for retaining the thread-shifters in their shifted position while the thread-carrier is traveling to 20 the opposite side of the warp, devices for releasing the thread-shifters at the end of such period, means for returning them from their shifted to their normal position, a thread-carrier and means for reciprocating it across 25 the warp, substantially as described.

38. In a loom, the combination of one or more thread-shifters arranged one on each side of the warp, a series of independently-movable slides, provided with the lugs 16 and 18, devices between the slides and thread-shifters adapted to be acted upon by any one of said series of slides, mechanism adapted to engage the lugs of the slides to reciprocate the same, and pattern-controlled mechanism 45 for throwing said slides into position for the lugs thereof to be engaged by their reciprocating mechanism, substantially as described.

39. In a loom, the combination of one or more thread-shifters arranged one on each side of the warp, each provided at its under side with teeth, means for shifting the thread-shifters to cause a proper thread to be presented to the thread-carrier, a spring-pressed pawl for engaging the teeth of the thread-shifter to hold it against rearward movement, devices for releasing said pawl from engagement with the teeth of the thread-shifter at a predetermined time, means for returning the thread-shifter to its normal position, a thread-carrier and means for reciprocating it across the warp, substantially as described.

40. In a loom, the combination of one or

more thread-shifters arranged one on each side of the warp, primary pattern devices, secondary pattern devices, intermediate mechanism between the thread-shifters and primary pattern devices a needle-bar for engaging said secondary pattern devices, means for reciprocating said needle-bar, and devices between the needle-bar and primary pattern devices whereby the operation of the primary pattern device is controlled, substantially as described.

41. In a loom, the combination of one or more thread-shifters arranged one on each side of the warp, a primary pattern-belt, provided with a parallel series of perforations, mechanism between the primary pattern-belt and thread-shifters, a director pattern-belt, provided with a single series of perforations, 80 a needle-bar for engaging the director pattern-belt, means for reciprocating said needle-bar, and intermediate devices between the said needle-bar and primary pattern-belt 85 whereby the movement of the latter is controlled by the former, substantially as described.

42. In a loom, the combination of one or more thread-shifters arranged one on each side of the warp, a series of independently-movable slides provided with lugs 16 and 18 the lugs on each slide being of different relative distances apart, devices between the slides and thread-shifters adapted to be acted upon by any one of said series of slides, mechanism adapted to engage the lugs of the slides to reciprocate the same, and pattern-controlled mechanism for throwing said slides into position for the lugs thereof to be engaged by their reciprocating mechanism substantially as described.

43. In a loom, the combination of one or more thread-shifters arranged one on each side of the warp, a perforated primary pattern-belt, a plurality of needles adapted to engage the perforations of the primary pattern-belt, means for moving said needles into engagement with the perforations of the primary pattern-belt, devices for elevating said needles above the primary pattern-belt at regular intervals, means for imparting a step-by-step progressive movement to the primary pattern-belt, intermediate mechanism between the needles and the thread-shifters, a director pattern-belt and means for imparting a continuous step-by-step progressive movement thereto, and devices under the control of the director pattern-belt whereby the progressive movement of the primary pattern-belt may be arrested or continued as desired, substantially as described.

44. In a loom, the combination of one or more thread-shifters arranged one on each side of the warp, primary pattern devices for controlling the movement thereof, devices intermediate of the thread-shifters and primary pattern devices, a director pattern-belt, the swinging frame N carrying the pawls 73 and 56, means for swinging said frame, the ratchet-

wheels 74 and 57, the plate 58 for elevating the pawls 56, the needle-bar 52 adapted to engage the director pattern-belt, means for reciprocating said needle-bar, the slide 53 for lifting the pawl 73 out of engagement with the ratchet 74, and the link 55 connecting the needle-bar 52 and the slide 53, substantially as described.

45. In a loom, the combination of one or more thread-shifters arranged one on each side of the warp, means for shifting the same to cause a proper thread to be presented to the thread-carrier, a thread-carrier having thread-grippers, and a depressing-plate for opening said grippers, means for reciprocating the thread-carrier across the warp, the arm 88 the slide 89^a connected to said arm and having an L-shaped slot therein, the lever 91 carrying a pin for engaging said slot, the spring 94 and means for imparting a reciprocating movement to the lever 91, substantially as described.

46. In a loom, the combination of the thread-carrier consisting of the gripper-jaws S. S' normally resting together, the arms 86 pivoted in the thread-carrier and carrying tapering pins adapted to be forced between the opposing faces of the gripper-jaws S. S' to open the same, a depressing-plate 87 on the thread-carrier for depressing said arms, devices for engaging the depressing-plate to open the gripper-jaws of the thread-carrier and devices

for closing the jaws, substantially as described.

47. The combination with the primary and director pattern devices, a bar for engaging the director pattern devices, means for positively lifting said bar from engagement with the said director pattern devices at regular intervals, devices intermediate the bar and the primary pattern devices whereby the operation of said primary pattern devices may be suspended or continued, substantially as described.

48. The combination with the primary and director pattern-cylinders and their attached ratchet-wheels, of the swinging frame, pawls carried by the swinging frame for engaging the ratchet-wheels of the director and primary pattern-cylinders respectively, a reciprocating bar engaging the director pattern-cylinder, a reciprocating slide, and a link connecting the slide and reciprocating bar whereby the slide is projected beneath or withdrawn from beneath the pawl of the primary ratchet-wheel, substantially as described.

In testimony whereof I have signed my name to this specification in the presence of two subscribing witnesses.

WILLIAM WEAVER.
